UNITED STATES PATENT OFFICE

JOHN E. CRADDOCK, OF BROOKLYN, NEW YORK

BALL-VENDING MACHINE

Application filed November 29, 1929. Serial No. 410,455.

This invention relates to ball vendors and in particular to mechanisms of this character employed in connection with amusement games or other devices in conjunction with which its use may facilitate operation.

5 A particular object of my invention is to provide a ball vendor which is electrically operated and which will speed up the earning capacity of an amusement game in connection with which it may be employed.

10 A still further object of my invention is to provide a device of the character referred to which will have few parts, which may be so built that the balls are quickly dispensed and held in position for the player to readily use; the machine being foolproof and of such character that its parts will not readily get out of order.

15 My machine contemplates the use of a ball holding shelf which acts as a receiver for balls returned from the counting device of a game or after a play has been completed, the shelf being held in its ball receiving position until the operation of mechanism which is set in motion by the insertion of a coin, the 20 operation of the mechanism taking place very quickly in order that no time will be lost in dispensing the balls to the player whereby a maximum use of the machine in play is afforded.

25 With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the 30 scope of what is claimed without departing from the spirit of the invention.

35 In the accompanying drawings:

40 Figure 1 is a view in perspective of a ball vending machine constructed in accordance with my invention, the ball receiving section being clearly illustrated as well as the dispensing portion of the machine.

45 Figure 2 is an enlarged section taken on the line 2—2 of Figure 1 and shows the relative arrangement of the operating parts of my mechanism.

50 Figure 3 is an enlarged view of the end of the machine illustrated in Figure 2, the parts thereof being shown in section to illustrate the relative positions of the operating mechanism with relation to the ball holding shelf.

55 Figure 4 is a section taken on the line 4—4 of Figure 3 and shows the construction of the ball holding shelf.

60 Figure 5 is a view in perspective of the coin contact arm and the drop arm which are employed as an important feature in the operation of my device, and

65 Figure 6 is a section in reduced scale taken on the line 6—6 of Figure 3, and showing the construction of the ball handling end of the machine.

70 Referring to the drawings in detail, 5 indicates generally the housing of my ball vending machine, the top of which may be sloped as at 6 and may have projecting therethrough, a coin slot 7 which, through the medium of a suitable flange 8 is secured to the top 6 of the housing. The housing is provided with an opening 9 at the front thereof and a portion of said opening is set off by the ball retaining strips 10 behind which are held, the balls to be dispensed. The extended portion of the housing indicated by the numeral 11 encases the operating mechanism and use is made of a partition, 12, see Figure 3, to separate the ball part of the housing from the mechanism which carries out the ball dispensing operation, the top of the mechanism chamber 13 being closed and the front thereof is arranged to receive a money drawer 14 which, 75 through the medium of any suitable lock 15 may be secured in position, the end of the drawer 14 being disposed beneath the coin drop 7 so that after a coin has been inserted and has performed its work, it will drop into the coin drawer 14 and may be readily removed by withdrawing the drawer.

80 As illustrated in Figure 6, particularly, the balls are supported behind the strips 10 through the medium of a shelf 16 which extends substantially the entire length of the vending machine and passes through a suitable opening 17 in the partition 12. This 85 90 95 100

shelf 16 through the medium of suitable hinges 18 is hinged for pivotal movement to the lowermost strip 10 and balls coming in through a suitable chute 19, which has been shown in outline in Figure 6, it being understood that the balls may be introduced into the vending machine in any particular manner, will ride down the inclined ledge 20 which, through the medium of a suitable bracket 21, is secured to the rear wall 22 of the vending machine and thence onto the shelf 16 to be held in the position indicated in outline between the edge of the incline ledge 20 and the strip 10.

15 The balls are indicated by the numeral 23 and after the shelf 16 has been operated in a manner to be hereinafter described, the balls drop upon the inclined bottom piece 24 which is positioned in the bottom of the vending machine and they therefore roll into the open box-like portion of the machine from which they may be taken at will by the player, it being understood that a certain number of balls are dispensed each time that 20 a coin is inserted in the coin drop. The ball vending machine may be provided with the legs 25, if desired, or it may be built directly into a counter or into any amusement game in connection with which it is employed.

30 The ends of the strips 10 are suitably secured in the partition 12 in one end, and at their other end, are secured in any suitable manner to the end wall of the machine so that they are rigid and are spaced the proper 35 distance apart so that the balls cannot be removed between them. Also, the lower strip 10 is the sole support, in the absence of a retaining detent, of the shelf 16 to which strip the latter is hingedly secured, as before 40 mentioned.

In the operation of my device, it will be presumed that the balls 23 occupy the shelf 16 in the ball compartment and are ready to be vended into the open space of the vending machine so that they may be used 45 by the player, it being understood that the balls are automatically returned from the point of play to the vending machine after they have operated a suitable scoring mechanism, as is common at amusement resorts.

50 A coin is dropped through the coin passage or drop 7, the coin being indicated by the numeral 26 in Figure 3, until it comes to rest upon the metallic coin contact arm 27 which has secured therein the metal pivot pin 28 which passes through the opposite sides of an arm 29 one side of which constitutes a coin drop arm 30, the opposite side being curved to provide the contact arm 27, before referred 55 to. The arm 30 projects beyond the contact housing 31, which is made of insulating material and which is provided with a central opening 32 in which operates the coin contact arm 27. The end of arm 30 has riveted there- 60 to a piece of insulation 70 as by rivets 71. The 65

pivot pin 28 is arranged to be connected through the medium of a wire 33, see Figure 2, with a source of power 34 and this power or current travels through the coin contact arm 27 and through the coin 26 to a pin 35 which is secured in the housing 31 and immediately below the outlet end of the coin drop 7. The tip end of the coin contact arm 27 is also positioned immediately below the lower edge of the coin drop 7 and opposite the pin 35 so that, as illustrated in Figure 3, a rest is provided for the coin 26 which makes contact between the arm 27 and pin 35 and permits the current that comes in on the line 33 to pass through the pin 28 through the contact arm 27, through the coin 26, out through the pin 35, through a wire 36 to a solenoid 37, positioned in the bottom of the vending machine in the mechanism chamber 13. The minus side of the solenoid coil 37 is connected to the return power circuit wire 38 through the wire 39.

The solenoid coil 37 being of the usual construction, is provided with a solenoid core 40, the upper end of which at one side is extended as at 41 to provide a contact engaging lip which, upon a downward movement of the core 40, presses against the spring contact arm 42 and causes it to complete a circuit through the contact arm 43, the arms 42 and 43 being suitably insulated as at 44 from each other, while the arm 43 is bracketed at one end as at 45 to be suitably supported on the rear wall of the vending machine housing. The arm 43 is connected by the wire 46 to the plus side of the power source while the upper arm 42 is connected through the medium of the wire 47 with a counting mechanism or other device used in the game and which has not been shown, it being the purpose of the mechanism to cut off the operation of the counter and return it to zero after a coin has been dropped in the slot so that the player cannot cheat by drawing an additional ball after he has already used up one set of balls to play a particular game.

In order that the solenoid may operate to vend the balls 23, the upper end of the solenoid is connected through the medium of the spring 48 with the under side of a detent arm 49, the spring 48 passing through an opening 50 in the shelf 16. The detent arm 49 at one end is turned down as at 51 and is connected by the spring 52 to the free end of the shelf 16. The detent arm 49 is hinged as at 53 to the shelf 16 and the detent or upstanding portion 54 of the arm is arranged to lie behind the upper end of a detent stop strip 55 which is secured to the partition 12. The detent 54 is held in the position illustrated in Figure 3 through the medium of the spring 52. As soon, however, as the circuit has been completed by the coin 26 and the solenoid operates, it will quickly pull down the core 40 with the result that the 55 60 65 70 75 80 85 90 95 100 105 110 115 120 125 130

5 spring 48 will be tensioned and will overcome the tension of the spring 52 tilting the 70 detent arm 49 until the upper end of the 75 detent 54 is disengaged from the detent strip 55 with the result that continued tension of the 80 spring 48 and the operation of the shelf 16 by reason of said tension will drop the 85 balls onto the inclined bottom 24.

10 The shelf 16 is provided with an open ended slot 57 to provide for the relative 100 movement of the depending portion 51 of the 105 detent arm 49. This detent arm, when it is held in its normal raised position and the 110 shelf is in a position to receive the balls as 115 they come off the ledge 20, maintains in contact, the contact arms 58 and 59 and a circuit 120 between the arms is provided through the medium of the wires 60 and 61 which 125 lead from the plug side of the power source so that the counting mechanism or other 130 mechanism controlled by the contacts 58 and 135 59 may be always in operation when the shelf 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

zero position. This forms no part of my invention and the operation of the switches is illustrated for the purpose of showing that a current can be controlled during the operation of the vending machine by the moving 70 part thereof. It will be understood, of course, that when the solenoid starts its downward movement, its movement is so quick that it will drop its full distance under the initial force given it by the energization of the coil 37 and will momentarily contact the parts 42 and 43 even after the coin contact arm 27 has been moved to a position to permit the coins to drop between it and the pin 35 and into the coin receptacle 14. 75 80 The action of the spring 68, then, will overcome the action of the spring 48 in concert with the de-energized coil core and will pull the shelf back up to its normal position and at the same time, the detent 54 riding over the face of the detent strip 55 will come to the upper end thereof and will snap into position behind it, as illustrated in Figures 2 and 3 and the mechanism will, at that time, be restored to its normal operating position 85 90 and will be ready to receive another coin as soon as the player has used up the balls that he has purchased with the previous coin.

It is evident, therefore, that I have provided an automatic ball vending machine 95 which may be used in conjunction with amusement devices and which may be hooked up electrically with a counting or other score device and which will control the operation of the score device so that no scoring may 100 be carried out during the vending operation of the machine.

It is evident also that I have provided a machine, the construction of which is simple and which is foolproof and which will quickly dispense balls so that the game may 105 be operated as rapidly as possible and therefore increase the income or revenue of a battery of machines as employed in an amusement resort.

It is evident also that my dispensing device is applicable to other types of machines and it is also evident that the wiring may be changed to perform other work upon completing of circuits and separation of contacts 110 115 as described.

While I have illustrated and described my invention with some degree of particularity, I realize that in practice various alterations therein may be made without departing from 120 the spirit of the invention or the scope of the appended claims.

What I claim is:

1. A ball vending machine comprising a ball shelf, a latch for sustaining the shelf 125 in ball supporting position, a solenoid for moving the shelf to non-supporting position, a coin drop, a contact arm, a pin coacting with the contact arm to provide a coin seat, a circuit including the solenoid, the arm and 130

the pin and completed by said coin, and means for moving the contact arm for unseating the coin and breaking said circuit.

2. A ball vending machine comprising a
5 tiltable ball supporting shelf, a detent member hinged to the shelf, a strip with which said detent engages to hold the shelf in ball supporting position, contacts arranged to be bridged by a coin to complete a circuit, a
10 solenoid in the circuit, means for moving one of the contacts to permit passage of the coin, and break of the circuit, a switch held closed by the detent member when the shelf is in supporting position, the solenoid acting
15 to disengage the detent and strip to tilt said shelf, and a switch arranged to be engaged and closed by the solenoid upon a detent disengaging action thereof.

3. A ball vending machine comprising a
20 ball shelf, means for sustaining the shelf in ball supporting position including a latch hinged to said shelf, and a detent strip engageable by said latch, a coin control mechanism including a solenoid for disengaging
25 said latch and strip to drop the shelf to non-supporting position, and a switch engageable by the solenoid in its latch disengaging movement to complete a circuit.

4. A ball vending machine comprising a
30 ball shelf, means for sustaining the shelf in ball supporting position including a latch hinged to said shelf and a detent strip engageable by said latch, a coin control mechanism including a solenoid for disengaging
35 the latch and strip to drop the shelf to non-supporting position, a coin drop, a contact arm, a pin coacting with the contact arm to provide a coin seat, a circuit including the solenoid, the arm and the pin and completed
40 by the coin, and means for moving the contact arm for unseating the coin and breaking the circuit.

In testimony whereof I have signed my
45 name to this specification this 28th day of October, 1929.

JOHN E. CRADDOCK. [L.S.]
